UNITED STATES PATENT OFFICE.

ALBERT ZOLLER, OF NEW YORK, N. Y.

HOSE-COUPING.

SPECIFICATION forming part of Letters Patent No. 298,150, dated May 6, 1884.

Application filed November 22, 1883. (No model.)

To all whom it may concern:

Be it known that I, ALBERT ZOLLER, a citizen of the United States, residing at New York, in the county and State of New York, 5 have invented new and useful Improvements in Hose-Couplings, of which the following is a specification.

This invention relates to that class of couplings in which the two hose-attaching pieces 10 engage with a coupling-piece; and it consists in the novel means hereinafter described for engaging one of the attaching-pieces with the coupling-piece, whereby a lock-joint may be produced by a very simple adjustment of 15 the parts.

In the accompanying drawings, Figure 1 is a longitudinal section of a coupling embodying my invention. Fig. 2 is a side view, partly in section, showing the parts separated. Fig. 3 is a face view of one of the attaching-pieces. Fig. 4 is a like view of the coupling-piece.

Similar letters indicate corresponding parts.

The letters A B designate the hose-attaching pieces, and C the coupling-piece. Both attaching-pieces A B are corrugated in the usual manner for properly retaining the hose, and at the inner end, where such pieces come in contact with each other, one, A, has a 30 groove, e, containing a suitable packing-ring, while at a suitable distance from the inner end the other piece, B, has a shoulder, f, whereby it engages with the coupling-piece C, a screw-nut, g, serving to hold it in position. The attaching-piece A also has a handle, h, for its convenient manipulation. On the coupling-piece C is cast or otherwise formed an internal flange, which is divided into two sections, i i, of substantially equal 40 length, by spaces or openings k k, and on the attaching-piece A are formed external lugs, l l, which are adapted to pass through such spaces between the flange-sections to enter the coupling-piece. The inner faces of the flange-sections i i are inclined, one similar to the other, and the lugs l l are so arranged relatively to these faces that if the lugs are brought into the coupling-piece and the latter is turned 45 in the proper direction the lugs engage with

the inclined faces to draw the attaching-pieces 50 toward each other, thus producing the desired coupling. In said inclined faces of the flange-sections i i are formed depressions o, which are adapted to receive the lugs l l, so that when the lugs are made to engage with 55 the faces, as stated, they are locked in position by entering either of the depressions. In the example shown the flange-sections i i and lugs l l are on the edge of the respective attaching-pieces. To facilitate the engagement of the lugs l l with the inclined faces k k, they are beveled in similar directions on the proper edges.

Heretofore the hose-attaching pieces of a hose-coupling have been provided, respectively, with external lugs and internal flange-sections, so that the lugs on one piece can be locked behind the flanges on the other piece, and in another instance metal pipe-sections have been provided at their adjoining ends 70 with lugs or flanges, so that the said ends can be drawn together by a collar having internal flanges or lugs. Such couplings do not constitute my invention, and are not claimed by me.

What I claim as new, and desire to secure by Letters Patent, is—

1. The combination, substantially as herein-before described, of the two hose-attaching pieces A and B, the former having the external lugs, l l, with the coupling-piece C, having the flange-sections i i and openings k k, and devices loosely confining the coupling-piece permanently in position on the attaching-piece B, but permitting its free rotation 85 thereon, substantially as described.

2. A hose-coupling consisting of the hose-attaching pieces A B, the former having the projecting lugs l l, and the other having the annular flange f, the coupling-piece C, having 90 the internal flange-sections, i i, and openings k k, and means for permanently holding the coupling-piece against the said flange, but permitting it to be rotated on the attaching-piece carrying said flange, substantially as 95 described.

3. A hose-coupling consisting of the following elements, to wit: the hose-attaching

pieces A and B, the former having the external lugs, *ll*, and the other having the annular flange *f* and screw-nut *g*, and the coupling-piece C, having the internal flange-sections, *i* 5 *i*, and openings *k* *k*, and loosely held between the flange and the nut, to permit its rotation on the hose-attaching piece B, substantially as described.

In testimony whereof I have hereunto set my hand and seal in the presence of two sub- 10 scribing witnesses.

ALBERT ZOLLER. [L. S.]
